DESIGN FOR AN ELECTRIC SWITCH HOUSING OR SIMILAR ARTICLE

William L. Butler and Nicholas J. Walsh, Schenectady, N. Y., assignors to Alpine Electric Corporation, Schenectady, N. Y., a corporation of New York

Application April 10, 1935, Serial No. 56,316

Term of patent 14 years

To all whom it may concern:

Be it known that we, William L. Butler and Nicholas J. Walsh, citizens of the United States, residing at Schenectady, county of Schenectady, State of New York, have invented a new, original, and ornamental Design for an Electric Switch Housing or Similar Article, of which the following is a specification, reference being had to the accompanying drawing, forming a part thereof.

The dominant feature of the design is the box-like housing or casing shown in full lines. As contemplated herein, the casing is composed of two parts held together, as indicated in dotted lines. Also indicated in dotted lines is a neck through which passes the usual pull chain, shown in dotted lines.

We claim:

The ornamental design for an electric switch housing, or similar article, as shown and described.
